COMBINED HOLDER FOR TOOTHPICKS OR THE
LIKE AND WRAPPER RECEPTACLE

Kermit E. Kerchberger, 1200 Duke Drive,
Bakersfield, Calif. 93305

Filed Dec. 23, 1965, Ser. No. 313

Term of patent 14 years

(Cl. D44—10)

Fig. 1

Fig. 2

FIGURE 1 is a perspective view of a combined holder for toothpicks or the like and wrapper receptacle showing my new design; and

FIGURE 2 is a side elevational view thereof.

The essential features of the design are shown in full lines.

I claim:

The ornamental design for a combined holder for toothpicks or the like and wrapper receptacle, as shown and described.
